Application April 7, 1931. Serial No. 528,344

2 Claims. (Cl. 155—41)

The invention relates to improvements in chairs and particularly to an improved chair having an ironing board mounted thereon in a manner to provide for its forming a part of said chair when not in use as an ironing board.

An object of the invention is to provide a novel chair having an ironing board mounted thereon with means for adjusting its position to provide a back for said chair.

Another object is to provide a chair having a pivotally mounted back adapted for use as an ironing board, with means for supporting the chair against tilting.

Another object is to provide a chair having an ironing board mounted thereon with improved supporting means adapted to be used as a step.

Another object is to provide an article of the character referred to, applicable for a plurality of uses, which may be inexpensively manufactured.

The foregoing and such other objects of the invention as will appear hereinafter as the description proceeds, will be more readily understood from a perusal of the following specification, reference being had to the accompanying drawing, in which:

Fig. 1 is a perspective view of the improved combination ironing board, chair, and step ladder.

Fig. 2 is a front elevational view of the improved article, showing the parts in the position shown in Fig. 1.

Fig. 3 is a side elevational view of the improved article with the ironing board in position for use.

Fig. 4 is a vertical central sectional view through the improved chair, showing the ironing board and step folded out of usable position.

The improved combination ironing board, chair, and step ladder preferably comprises a seat 11 having front legs 12 and arcuate rear legs 13. The rear legs 13 preferably extend upwardly and rearwardly of the seat 11 to provide extensions 14, between the upper extremities of which is pivotally mounted an ironing board 15. The mounting for the ironing board preferably comprises a laterally extending cross member 16 fixedly secured on the under side of the board 15, adjacent one end, having pins or a shaft 17 extending therethrough and journaled in the arms or extensions 14.

A prop or support 18 preferably is secured by a hinge 19 to the under side of the ironing board 15, adjacent the free end. When the board 15 is in position for use as an ironing board, the free end of the support 18 engages in a suitable recess

21 provided in a cross strip 22 extending between the legs 13 for supporting the rear end of the seat 11.

When the ironing board is not in use, said board may be swung upwardly and rearwardly 60 about the pivot 17, and against the rear side of the cross strip 22 to provide a back for the chair. When the ironing board is in this position the support 18 is frictionally held folded substantially parallel with the ironing board 15 by a 65 suitable spring clamp 23.

It will be noted upon reference to Fig. 3 that the ironing board, when positioned for use, extends forwardly of the front of the chair. It is, therefore, necessary to provide suitable means 70 to prevent tilting of the chair when weight is placed upon the forward end of the board. To this end, a suitable support and step 24 is arranged to extend forwardly of the chair. This support preferably comprises a semicircular piece 75 of material 25 extending outwardly from and fixedly secured to a rotatably mounted rung 26. The rung 26 extends horizontally between the front legs 12 of the chair substantially midway between the seat and the floor. When the ironing board is positioned for use, the support or step 24 is, as aforementioned, positioned to extend forwardly of the chair, as shown in Figs. 1 and 3, and is supported in this position by a leg 27, extending perpendicular from one side of the 80 member 25, and brace 28 which abuts the usual seat supporting strip 29 extending between the legs 12.

By folding the ironing board out of usable position to provide a back for the chair, the chair proper and the step 24 provide an article which may be used as a step ladder. To use the improved article as a chair, the support member 24 is swung downwardly and inwardly under the seat. It is secured substantially in the position 95 shown in Fig. 4 by a suitable spring clip 29, mounted on the under side of the seat, which engages the leg 26.

It can readily be understood that a very practical, inexpensive article of furniture is provided by the improved structure, said article being applicable to a plurality of uses, and it is to be further understood that the improved structure may embody certain variations in structural detail without departing from the spirit of the invention or the scope of the appended claims.

We claim:

1. A combination article of furniture for purposes described, comprising a chair having a seat, back-uprights and legs, an ironing board piv- 110

oted adjacent one end between the upper end of said back-uprights, a support hingedly connected with said board, a cross bar between the back-uprights adjacent the seat, a socket in said cross bar adapted to receive the end of the support when the ironing board is positioned horizontally, a support hingedly mounted between the legs below said seat adapted to be extended forwardly of the chair to prevent tilting, and an extension on said support adapted to co-operate with a cross bar extending between said legs to hold said support in its forwardly extended position.

2. A combination article of furniture for purposes described, comprising a chair having a seat, back-uprights and legs, an ironing board pivoted adjacent one end between the upper end of said

back-uprights, a support hingedly connected to said board, a cross bar between the back-uprights adjacent the seat, a socket in said cross bar adapted to receive the end of the support when the ironing board is positioned horizontally, a support hingedly mounted between the legs below said seat adapted to be extended forwardly of the chair to prevent tilting, an extension on said support adapted to cooperate with a cross bar extending between said legs to hold said support in its forwardly extended position, said support providing a step to facilitate access to the chair seat when the ironing board is positioned vertically. 80 85
